UNITED STATES PATENT OFFICE.

KAZIMIER CHROBAK, OF ROSEMONT, WEST VIRGINIA, ASSIGNOR OF ONE-THIRD TO
MIKE SEMERYK, OF ROSEMONT, WEST VIRGINIA.

RAILROAD-GATE.

1,332,710.

Specification of Letters Patent.

Patented Mar. 2, 1920.

Application filed December 8, 1919. Serial No. 343,175.

To all whom it may concern:

Be it known that I, KAZIMIER CHROBAK, a citizen of Poland, residing at Rosemont, in the county of Taylor and State of West Virginia, have invented certain new and useful Improvements in Railroad - Gates, of which the following is a specification.

This invention relates to an improved railroad gate and the principal object of the invention is to provide an improved actuating means for lowering the gate, the actuating means being so constructed that it may be operated from the train and will immediately cause raising of the gate upon passage of the train.

Another object of the invention is to provide an operating mechanism for a railroad gate which shall be comparatively simple in construction and comprising a comparatively few parts, all of which will be strong and durable and not liable to easily get out of order.

The invention is illustrated in the accompanying drawings throughout which like reference characters designate corresponding parts and wherein,

Figure 1 is a fragmentary sectional view in perspective of one-half of the mechanism,

Fig. 1^a is a similar view of the other half thereof, and

Fig. 2 is an end elevational view either looking to the left of Fig. 1 or to the right of Fig. 1^a.

The actuating mechanism for the railroad gates 5 will be mounted upon the ties 6 outwardly of the outside rail 7 of said track. As will presently become apparent, portions of the mechanism will also extend under ground at the crossing or roadway. The gates 5 are of conventional construction and are pivotally connected with the standards 8 through the medium of the shafts or axles 9. The standards 8 are provided with transverse pins 10 beneath the axles 9 and a spring 11 is partially wound around each pin, one free end of each spring being extended to bear against the under side of a gate 5 so as to exert its force for the purpose of expediting the raising of said gate. This free end of the spring is secured in any suitable manner to said gate whereby, when a pull is exerted upon said end by means of the train operated mechanism to be described, the gate will be caused to lower.

A pair of brackets 12 are mounted upon

the spaced ties for each of the ramps 13, which ramps each are pivotally connected to the upper ends of links 14 as at 15, the lower ends of said links being pivotally mounted in the brackets 12. The pivotal 60 mountings for the lower ends of the links 14 comprise shafts 16, one of which is extended laterally as at 17 away from the rail 7 and journaled in the adjacent standard 8 beneath the pin 10. A bell-crank lever 18 is fastened upon the outer end of each shaft extension 17.

A suitable flexible member such as a cable 19 is attached to the before mentioned free end of spring 11 and extends downwardly 70 from one gate 5 around a guide pulley 20 and then transversely of the crossing or roadway through a conduit 21 where the same is attached to the lower end of the vertical arm of the bell-crank lever 18 as 75 shown in Fig. 1. Another similar cable 22 (see Fig. 1) has one end attached to the free end of the spring 11 of Fig. 1 and extends downwardly around a guide pulley 20' and then transversely of the roadway 80 through the conduit 21 where it has its other end attached as at 23 to the lower end of the vertical arm of the other bell-crank lever 18. It will thus be seen that cable 19 has one end attached to spring 11 of the gate shown in 85 Fig. 1^a and has its other end attached to the vertical arm of the bell-crank lever 18 in Fig. 1, while cable 22 has one free end attached to the spring 11 of Fig. 1 and has its other end attached to the vertical arm 90 of the bell-crank lever 18 in Fig. 1^a. By this arrangement both gates 5 are simultaneously operated when either one of the ramps 13 are disposed. Numerous devices are well known in the art for automatically 95 depressing the ramps and the same may reside in a wheel 24 depending from the train in the path of the ramp.

The operation of the present invention may be briefly described as follows: Assuming 100 that a train provided with the wheel 24 is approaching from the right of Fig. 1 as indicated by the arrow a, said wheel will depress the ramp 13 and thereby cause swinging movement of the links 14. Such swinging movement of the links 14 causes rotary movement of the shaft 16 which has the extension 17 and also causes rocking movement of bell-crank lever 18 in a direction 105 whereby the normally horizontal arm of the 110

latter swings downwardly. By reason of the connection 25 between said normally horizontal arm and the spring 11, this downward movement of said arm causes a pull to be exerted to effect lowering of the gate 5 of Fig. 1. When this operation is taking place, a slack is produced in cable 23 adjacent the standard 8 of Fig. 1 and a pull is exerted upon cable 19 by reason of its connection 10 to the vertical arm of bell crank lever 18 of Fig. 1. This pull upon cable 19 is transmitted to the gate 5 of Fig. 1^a to cause it also to lower. On the other hand, the reverse operation would take place if the train 15 were approaching the ramp of Fig. 1^a in the direction indicated by the arrow *b*. Obviously, when the wheel 24 ceases to press the ramp 13, the springs 11 immediately cause the gates 5 to return to the normal positions 20 thereof as shown. It is not absolutely necessary that the springs operate to raise the gates 5 as said gates may be weighted in the usual manner so as to normally assume a raised position. In this case the springs 25 would merely act to return the parts of the actuating mechanism to their normal positions.

From the foregoing description it is believed that the construction and operation 30 as well as the advantages of the present invention will be readily understood and appreciated.

It is to be understood that minor changes 35 may be made in the details of the invention without departing from the spirit and scope of the same as claimed.

What I claim as new is:—

1. In a railway gate structure, the combination of a pair of normally open gates, a 40 pair of rotary shafts each extending from a point adjacent the track to one of said gates, means adapted to be engaged by an operating member on an approaching car to rotate either of said shafts, bell-crank levers fastened upon said shafts adjacent said gates and normally disposed with one arm depending in a substantially vertical position and

the other arm projecting forwardly in a substantially horizontal position, cable connections between the free end of the horizontal arm of each bell-crank lever and one of said gates whereby downward movement of said horizontal arm will cause lowering of the gate to which it is connected, flexible operative connections between one of said gates 50 and the free end of the vertical arm of the bell-crank lever which is associated with the other gate, similar connections between said other gate and the free end of the vertical arm of the other bell-crank lever whereby rotation of either of said shafts by car actuation will cause lowering of both of said gates. 55

2. In a railway gate structure, the combination of a pair of normally open gates, a pair of rotary shafts each extending from a 60 point adjacent the track to one of said gates, means adapted to be engaged by an operating member on an approaching car to rotate either of said shafts, bell-crank levers fastened upon said shafts adjacent said gates 65 and normally disposed with one arm depending in a substantially vertical position and the other arm projecting forwardly in a substantially horizontal position, cable connections between the free end of the horizontal arm of each bell-crank lever and one of said gates 70 whereby downward movement of said horizontal arm will cause lowering of the gate to which it is connected, flexible operative connections between one of said gates 75 and the free end of the vertical arm of the bell-crank lever which is associated with the other gate, similar connections between said other gate and the free end of the vertical arm of the other bell-crank lever whereby rotation of either of said shafts by car actuation 80 will cause lowering of both of said gates, and a spring associated with said connections and each of said gates to return the former to their normal positions upon passage of 90 the car and return of the gates to their normal open positions.

In testimony whereof I affix my signature.
KAZIMIER CHROBAK.
